UNITED STATES PATENT OFFICE.

JAMES PRESTON, OF TUCKAHOE, NEW YORK; LUCY PRESTON EXECUTRIX OF SAID
JAMES PRESTON, DECEASED.

CIGARETTE-MAKING DEVICE.

1,136,720.

Specification of Letters Patent. Patented Apr. 20, 1915.

Application filed April 22, 1914. Serial No. 833,685.

To all whom it may concern:

Be it known that I, JAMES PRESTON, a citizen of the United States, and a resident of Tuckahoe, in the county of Westchester and State of New York, have invented a new and Improved Cigarette-Making Device, of which the following is a full, clear, and exact description.

My invention relates to a device to be carried in the pocket by individual smokers, for forming cigarettes as required for immediate use.

More particularly the invention is designed to produce a device of the indicated character, by means of which a cigarette wrapper may be properly rolled and filled with fine cut tobacco of the general character employed in what is known as Cuban cigarettes, although the device is applicable for forming cigarettes from tobacco generally.

In carrying out the invention, use is made of a tubular structure presenting sections constituting a means for the rolling and filling of a cigarette wrapper. The sections are open along one side, and thus have approximately a semicylindrical or trough-like formation. The sections are co-axial or approximately so, and the one section is adapted to be turned through an angle about the other section, to bring the open sides of the sections more or less into register to receive the charge of tobacco, or to close the side opening and clamp an edge of the cigarette wrapper. With the wrapper thus clamped it may be rolled around the exterior of the sections with the charge of tobacco therein. Associated with the sections referred to and formed by the rear ends thereof, is an enlarged tubular body portion adapted to receive a surplus of tobacco in the charging of the filling and forming sections so as to insure an available supply of tobacco in the device for the filling of the rolled wrapper. In connection with the tubular sections of the body portion, a combined lock and stop is provided to limit the turning movement of the sections and prevent axial displacement of the latter. As a precaution, having in view the possible clinging of the tobacco, a follower device is provided, arranged to be brought into action for forcing the tobacco into the rolled wrapper, as the device is withdrawn from the wrapper.

The invention will be particularly explained in the specific description following.

Reference is to be had to the accompanying drawings forming a part of this specification, in which similar characters of reference indicate corresponding parts in all the views.

Figure 1 is a plan view of a cigarette making device constituting one practical embodiment of the invention, the wrapper-forming and filling sections being shown with their side openings in register, that the device may receive a charge of tobacco, a part of the body portion of the device being broken away; Fig. 2 is a similar view with the wrapper in position and in rolled form; Figs. 3, 4 and 5 are diagrammatic end views; Fig. 3 shows the semi-cylindrical sections in the position illustrated in Fig. 1, and charged with tobacco, a cigarette wrapper being also indicated; Fig. 4 shows the one semi-cylindrical section turned to close the side opening of the other section, and clamping the edge of the wrapper; and Fig. 5 shows the semi-cylindrical sections in the position indicated in Fig. 4, and with the wrapper rolled thereon; Fig. 6 is a cross sectional view of the upper portion of the device, on the line 6—6 of Fig. 1, parts being omitted; Fig. 7 is a partial vertical section showing the filling elements partially withdrawn from the rolled wrapper, and the latter partially filled; and Fig. 8 is a perspective view of the follower.

In constructing the device in accordance with the illustrated example, a tubular wrapper rolling and filling structure is provided, presenting inner and outer sections 10, 11, each of which is open along a side thereof, as at 10^a, 11^a. The said sections are thus approximately semi-cylindrical in cross section, being in practice, slightly greater than semi-cylindrical, to insure the retention of a charge of tobacco. The sections are continuous with a cylindrical body portion comprising an inner tubular member 12, and an outer tubular member 14 communicating with the sections 10, 11, preferably through the medium of a tapered portion 15. The inner tubular portion 12 may have a knurled head 13, for turning the same in the outer cylindrical portion 14, whereby a relative turning movement of one section 11 about the companion

section 10 is effected. With the described construction, when the sections 10, 11, are turned to bring their open sides into register, as in Figs. 1 and 3, the said sections 5 have a trough-like formation for receiving a charge of tobacco, as indicated by the letter B.

In charging the device it may be so tilted as to cause a surplus of tobacco to run into 10 the hollow body portion. The device having thus been charged with tobacco, one longitudinal edge portion of a wrapper A is entered through the open sides close against one side wall, outside of the tobacco B, as 15 indicated in Fig. 3, and a relative turning movement is given to the sections to cause the one section, as 10, to close the opening 11 in the other section, and at the same time clamp the edge of the wrapper A between 20 adjacent longitudinal edge portions 16, 17, of the sections, as indicated in Fig. 4. It will be observed from a comparison of Figs. 1 and 2, that the wrapper A is so placed that the front end thereof will extend beyond 25 the device. After the wrapper A has been clamped between the opposed edges 16, 17, the device is turned bodily to roll the wrapper onto the tubular forming and filling device, as shown in Figs. 2 and 5. The projecting end of the wrapper indicated in Fig. 30 2 is then tucked in to effect a closure of the outer end of the wrapper. The sections are now given a slight retrograde turning movement sufficient to release the clamped inner 35 edge of the rolled wrapper, whereupon the device may be up-ended, disposing the front end downwardly, and then gradually withdrawn from the wrapper, allowing the filling of tobacco to gravitate into the 40 rolled wrapper. If necessary, the outer longitudinal edge of the wrapper may be wetted to cause it to adhere sufficiently to prevent unrolling, as is customary in the making of cigarettes by users. 45 A sufficient quantity of tobacco to fill the rolled wrapper is insured by reason of the surplus in the hollow body portion. It will thus be seen that the sections constitute a tubular former about the exterior 50 of which the wrapper may be rolled while the interior of the former presents a chamber for the tobacco.

In order to limit the relative turning movement of the tubular members 12, 14, 55 of the body portion, a resilient tongue 18 is produced on the inner member 12 by forming a U-shaped slot or cut 19, leaving the said tongue integral at its base with the body portion 12. The free end of the tongue 60 is projected through a lateral opening 20 in the outer tubular member 14, and said free end may be return-bent, as at 21, if desired. It will be seen that the tongue 18 thus constitutes a stop to limit the turning of the 65 body members in either direction. More-

over, the said tongue forms a lock to prevent axial displacement of the members.

Ordinarily, in withdrawing the forming and filling sections from the rolled wrapper, a slight jarring of the tobacco will suffice to 70 detach the tobacco particles and permit them to gravitate into the rolled wrapper from the up-ended device. As a precaution, however, looking to the possibility of the tobacco clinging to the device, I provide a follower 75 that may be brought into requisition. The said follower preferably consists of a ring 22 loosely encircling the body portion and having a forwardly projecting finger 23, which is inturned at its free end as indicated at 24. Ordinarily, and when not required for use, the ring 22 will be at the rear end of the body portion adjacent to the knurled head 13, in which position the finger 23 will range forwardly along the 80 body, being of a length to terminate at the cylindrical portion adjacent to the tapered intermediate portion 15 of the device. The finger has more or less resiliency and is strained to be slightly under tension, with 85 the inturned free end 24 in frictional engagement with the exterior surface of the tubular member 14, so that the frictional engagement will hold the follower in position. 90

When the follower is required for use it may be slid forwardly and is free to be turned to insure the proper positioning of the finger to act as a follower. It is to be understood that if the follower is to be used, 10 the sections are turned to produce a free side opening between the opposed edges 16, 17, for the entrance of the end 24 of the follower. By reason of the loose fit of the ring 22 the finger may be rocked downwardly to engage the tobacco in the sections 10, 11. Thus, as the device is withdrawn from the rolled wrapper, the advancing follower will insure the loosening of the tobacco, should any tend to cling against the 11 inner surface of the device.

The described manner of forming the wrapper enables me to properly make cigarettes from loose tobacco such as employed in Cuban cigarettes, it being well known 11 that the rolling of cigarettes from such tobacco by ordinary methods requires considerable expertise, whereas with my device a cigarette may be formed from such tobacco with great facility.

In referring to the wrapper A, it is to be understood that paper, tobacco, or any other suitable material may be employed for the purpose.

The described construction affords a practical means for carrying my invention into effect, and I would state in conclusion that I do not limit myself strictly to the mechanical details herein illustrated, since manifestly the same can be considerably 11

varied without departure from the spirit of the invention.

Having thus described my invention, I claim as new, and desire to secure by Letters

5 Patent:

1. A device of the character described, comprising a tubular wrapper rolling and filling means formed of sections open along a side thereof and open at an end thereof, 10 and mounted to turn one on the other through an angle, to positions to dispose the sections in trough-like form, with the open sides in register, or to positions with one section closing the side opening of the companion section, the two sections in the latter position presenting jointly an exterior surface around which a cigarette wrapper may be rolled, the sections permitting an endwise removal of the rolled wrapper, and the said 15 open end of the sections forming an outlet for the tobacco into the rolled wrapper, longitudinally of the sections, as the said wrapper is removed endwise.
2. In a cigarette making device, a tubular 20 wrapper rolling and filling means comprising two approximately semi-cylindrical sections adapted to turn one on the other, to a position with one section closing the side opening of the other to constitute a trough-like receiver adapted to hold a charge of tobacco, or to a position with one section closing the other, said sections having an open end, the sections presenting opposed longitudinal edges meeting to clamp the edge of 25 a wrapper, whereby a bodily turning of the device will roll the wrapper on the exterior of the said charged tubular means, the sections permitting an endwise removal of the rolled wrapper and the said open end of the 30 sections forming an outlet for the tobacco into the rolled wrapper, longitudinally of the sections, as the rolled wrapper is removed endwise.
3. In a cigarette making device, a tubular 35 wrapper rolling and filling means comprising approximately semi-cylindrical sections arranged to turn at an angle relatively to each other, to present registering open sides for receiving a charge of tobacco, or to effect 40 a closure of said open sides, said section having an open end, and means to lock said sections against longitudinal displacement and limit the relative turning movement thereof, the sections permitting an endwise 45 removal of the rolled wrapper and the said open end of the sections forming an outlet for the tobacco into the rolled wrapper, longitudinally of the sections, as the rolled 50 wrapper is removed endwise.
4. In a cigarette making device, a tubular 55 wrapper rolling and filling means, comprising approximately semi-cylindrical sections arranged to turn through an angle relatively to each other, to present registering open 60 sides for receiving a charge of tobacco, or

to effect a closure of said open sides, the inner one of said sections having a transversely disposed tongue, and the other of said sections having an opening through which the said tongue projects, said tongue 70 limiting the turning movement of the sections and preventing longitudinal displacement thereof.

5. In a cigarette making device, a tubular 75 wrapper rolling and filling means comprising approximately semi-cylindrical sections adapted to turn one on the other and having an open end and opposed longitudinal, beveled edges, to clamp a cigarette wrapper and hold the same, the said sections turning 80 one on the other to positions with one section closing the side of the other section, the two sections in the said positions presenting jointly an exterior surface around which a cigarette wrapper may be rolled and then 85 removed endwise, the said open end of the sections forming an outlet for the tobacco into the rolled wrapper, longitudinally of the sections, when the said wrapper is withdrawn endwise.

6. In a device of the character described, a tubular body composed of inner and outer cylindrical members, a tubular wrapper rolling and filling extension communicating with the tubular body, and consisting of 90 mating sections each of which is open along a side thereof and at an end thereof, the said sections turning one on the other through an angle to positions with one section closing the open side of the other section in response to a relative turning of the body members, the two sections in the said positions presenting jointly an exterior surface 95 around which a cigarette wrapper may be rolled and then removed endwise, the said 100 open end of the sections forming an outlet for the tobacco into the rolled wrapper, longitudinally of the device, when the said wrapper is withdrawn endwise.

7. A cigarette making device comprising a 110 hollow body formed of inner and outer cylindrical members and open at the front for the entrance of tobacco, and semi-cylindrical sections respectively in fixed relation to the said inner and outer members 115 and in communication with the interior of the said body for the passage of tobacco to and from the body, the said sections being adapted to turn the one on the other in response to the relative turning of the body 120 sections.

8. In a cigarette making device, a hollow 125 body formed of inner and outer cylindrical members adapted to turn relatively to each other, and a tubular wrapper rolling and filling means consisting of approximately semi-cylindrical sections in fixed relation to the respective body members, and turning one on the other with the relative turning of the body members, opposed longitudinal 130

4
edges of the said sections constituting a clamping means to clamp an edge of a wrapper and cause the wrapper to be rolled onto the exterior of the said sections when the 5 latter are turned bodily.

9. In a cigarette making device, a hollow body formed of inner and outer cylindrical members adapted to turn relatively to each other, each having forwardly tapered portions at the front end, and a tubular wrapper rolling and filling means consisting of approximately semi-cylindrical sections in fixed relation to the respective tapered portions and turning the one on the other with 10 the relative turning of the body members, opposed longitudinal edges of the said sections constituting means to clamp the edge of a wrapper.

10. In a cigarette making device, a body, 20 a tubular wrapper rolling and filling means formed of sections each open along a side thereof and adapted to turn one on the other, an element slideable on the exterior of the body and on the said tubular means, and 25 having a forwardly-projecting resilient

finger constituting a follower to dislodge tobacco from the said tubular means, the said finger being adapted to enter between opposed longitudinal edges of the said sections.

11. In a cigarette making device, a body, a tubular wrapper rolling and filling means formed of sections each open along one side thereof and adapted to turn one on the other, a ring adapted to slide and to rock 35 on the body and movable from the latter along the said tubular means, the said ring having a forwardly-projecting finger constituting a follower to dislodge tobacco from the said tubular means, said finger being 40 adapted to enter between opposed longitudinal edges of the said sections.

In testimony whereof I have signed my name to this specification in the presence of two subscribing witnesses.

JAMES PRESTON.
